This invention relates to new compounds which are particularly useful for the treatment of heart arrhythmias.

Previously it has been proposed to use procaine or procaineamide for the treatment of heart arrhythmias (D. L. Burstein, Anesthesiology 7 (1946), p. 113, and K. Berry et al., Am. J. Med. 11 (1951), p. 431). It

having from 1 to 3 carbon atoms, and R_6 is an alkylene group containing from 1 to 4 carbon atoms; and

X^- is the anion of a physiologically acceptable acid such as

and the like.

By lower alkyl and lower alkoxy groups are meant groups which contain no more than 5 carbon atoms.

Suitable compounds within the scope of the present invention are the following:

has, however, now been shown that those compounds are effective for only a short duration and that in case of over-dosage they cause an undesired stimulation of the central nervous system combined with an undesired depressive action on the respiration and the cardiovascular system.

One object of the invention, therefore, is to provide a new class of compounds which will control heart arrhythmias for relatively prolonged times.

Another object of the invention is to provide a new class of compounds which will control heart arrhythmias without producing undesirable side effects.

Still another object of this invention is to provide a new method of treating heart arrhythmia.

Additional objects of this invention are to provide a method of synthesizing the compounds of this invention and new intermediate compounds useful in such synthesis.

Other objects and advantages of the invention will become apparent from the following description.

According to the present invention, it has been discovered that the compounds hereinafter described are effective against arrhythmias. These new compounds are particularly valuable because they are effective for a relatively long duration, and they have an insignificant stimulating effect on the nervous system.

The compounds of the present invention have the general formula:

where:

A and B are the same or different, straight or branched alkylene groups containing from 1 to 4 carbon atoms;

R_3 and R_4 are the same or different lower alkyl or, lower alkoxy groups.

n and m are integers from 0 to 3, inclusive.

Z^+ is selected from the class consisting of

60

where

R_1 and R_2 are the same or different alkyl groups

with a compound of the formula:

(3)

or by reacting a compound of the formula:

(4)

with a compound of the formula R_2X where R_7 is either H or R_1 . Either of these reactions will form a compound of the generic formula

20

The symbols are as hereinabove defined. When Z includes a heterocyclic ring the reaction between intermediates (2) and (3) must be used.

In addition, according to the present invention, certain intermediate compounds have been discovered. These compounds are secondary and tertiary amines having the same formula:

The symbols in the above formula are herein defined. These intermediates are particularly useful where a compound in which the substituents R_1 and R_2 on the quaternary nitrogen are different radicals. An illustrative compound within this class is N -bis-(2,6-dimethylphenylcarbamoylmethyl)-ethylamine having the general formula:

The invention is illustrated by but not limited to the following examples.

EXAMPLE 1

11.7 g. of diethylaminoaceto-2,6-dimethyl anilide and 9.9 g. of chloroaceto-2,6-dimethyl anilide are dissolved in 25 ml. of xylene to which is added 0.1 g. of potassium iodide.

The reaction mixture is refluxed for 10 hours. After cooling, the precipitated crystal mass is suctioned off and washed with ether. After recrystallization from ethanol-ether, the reaction product has a melting point of 224-225° C. (decomposition). It is of the following formula

EXAMPLE 2

A solution of 10.3 g. dimethylaminoaceto-2,6-dimethyl anilide and 9.9 g. of chloroaceto-2,6-dimethyl anilide in 25 ml. of xylene to which is added 0.15 g. of potassium iodide is refluxed on oil bath for 7 hours. After cooling to room temperature the xylene is decanted off and the remaining semicrystalline substance is dissolved in ethanol. Through

addition of dry ether the reaction product is precipitated in crystalline form and is further purified by a recrystallization from ethanol-ether. The product melts at 217-218° C. under decomposition and has the formula given below

EXAMPLE 3

In an analogous way 12 g. of dimethylaminoaceto-2,6-dimethyl anilide and 9.9 g. of chloroaceto anilide are reacted in 25 ml. of xylene. The reaction product is purified by recrystallization from ethanol-ether. The substance melts at 143-144° C. under decomposition and has the following formula

EXAMPLE 4

19 g. of dimethylaminoaceto anilide and 17.8 g. of chloroaceto anilide are dissolved in 50 ml. of xylene and to this is added about 0.2 g. of potassium iodide. The reaction mixture is refluxed for 45 minutes. The crystal mass formed is filtered off on the following day and is recrystallized from ethanol-ether. The pure substance melts at 172-173° C. under decomposition. The quaternary salt formed has the following formula

EXAMPLE 5

19.2 g. of dimethylaminoaceto-2-methyl anilide, 18.3 g. of chloroaceto-2-methyl anilide and about 0.2 g. of potassium iodide are dissolved in 50 ml. of xylene and heated on a steam bath for one hour. An oil gradually separates which crystallizes after cooling to room temperature. The reaction product is purified by recrystallization from ethanol-ether. It melts at 165-166° C. under decomposition and has the formula given below.

EXAMPLE 6

In an analogous way, by reacting α -dimethylamino-propio-2,6-dimethyl anilide and chloroaceto-2,6-dimethyl anilide, the following compound is prepared

This compound melts at 214-216° C. under decomposition.

5

EXAMPLE 7

Starting from dimethylaminoaceto-2,6-dimethyl anilide and chloroaceto-2,4-dimethyl anilide, the compound

is prepared. Its melting point is 177–178° C. under decomposition after a recrystallization from ethanol-ether.

EXAMPLE 8

Starting from dimethylaminoaceto-2,4,6-trimethyl anilide and chloroaceto-2,6-dimethyl anilide, the compound

is prepared. The melting point is 183–184° C. under decomposition after a recrystallization from ethanol-ether.

EXAMPLE 9

19.2 g. of dimethylaminoaceto-2-methyl anilide and 25 18.8 g. of chloroaceto-2,6-dimethyl anilide are dissolved in 50 ml. of acetonitrile and then 0.2 g. of KI is added, and the mixture is boiled for 2.5 hours. The crystal mass which is precipitated on cooling is recrystallized in ethanol-ether. The substance melts at 182–184° C. under decomposition and is of the following structure

6

ing point 210–211° C. under decomposition and has the following formula

EXAMPLE 12

To a solution of 18.0 g. of N-bis-(2,6-dimethylphenyl)-carbamoylmethyl-ethylamine in 90 ml. of acetone is added 90 ml. of a solution of methylbromide in acetone containing 0.5 of methylbromide per ml.

The reaction mixture is left at room temperature for 5 days during which time the reaction product is crystallized. The substance is filtered off and purified by recrystallization in ethanol-ether. The pure product melts at 194–195° C. under decomposition and is of the following formula

EXAMPLE 13

11.7 g. of α -dimethylaminobutyro-2,6-dimethyl anilide and 8.5 g. of chloroaceto anilide are dissolved in 50 ml. of xylene. To this is added 0.2 g. of KI and the mixture is reflux boiled for 1 hour. There is gradually separated an oil which crystallizes in the course of a day. The crystal mass formed is recrystallized in a mixture of dry ethanol and dry ether. The product melts at 133–135° C. and is of the formula

EXAMPLE 10

In an analogous way, starting from pyrrolidinoaceto-2,6-dimethyl anilide and chloroaceto-2,6-dimethyl anilide, the following compound is prepared

After a recrystallization from ethanol-ether, the compound melts at 227–228 C. under decomposition.

EXAMPLE 11

To a solution of 11.9 g. of dimethylaminoaceto-2,6-dimethoxy anilide and 11.5 g. of chloroaceto-2,6-dimethoxy anilide in 50 ml. of xylene is added 0.2 g. of KI and the mixture is boiled under reflux for 1.5 hours. The crystal mass precipitated on cooling is purified by recrystallization from ethanol-ether, leaving a product with the melt-

For an illustration of the pharmacological action and usefulness of the compounds thus prepared, tests have been made on their antiarrhythmia action in dogs according to Harris (A. S. Harris, Circulation I (1950), 1318). In Table I below, column (a) gives the dose necessary for the elimination of arrhythmias of the sinus rhythm in unanesthetized "coronary dogs," column (b) gives the dose which produces a prolongation of the duration of the electrocardiographically determined PQRS-complex, which means the dose that diminishes the impulse conduction velocity within the heart and thereby reduces the risk of ventricular fibrillation; and finally, column (c) gives the dose which produces a lowering of the blood pressure. In the same table, column (d) gives the dose necessary for a lowering of the heart frequency in anesthetized vagotomized and thoracotomized dogs and cats; column (e) gives the dose which causes a prolongation of the duration of the PQRS-complex and thereby prevents or shortens the auricular flutter caused by the application of an acetylcholine moistened cotton wad on the wall of the right auricle; and finally column (f) gives the amount of the particular compounds necessary for a lowering of the blood pressure.

Table I

Compound No.	Number of "coronary dogs"	Effective dose in mg./kg. (not anesthetized "cor. dogs") ¹			Number of cats and/or dogs	Effective dose in mg./kg. (anesthetized cats and/or dogs) ¹		
		Normalizing of the sinus rhythm	Prolongation of the PQRS-compl. ²	Lowering of the blood pressure		Lowering of the heart frequency	Prolongation of the PQRS-compl. ²	Lowering of the blood pressure
		<i>a</i>	<i>b</i>	<i>c</i>		<i>d</i>	<i>e</i>	<i>f</i>
I	2	0.5	0.5	-----	5	0.5-1	-----	0.5
II	1	1.2	1.2	-----	2	1.2	1.2	1.2
III	3	2	4	-----	9	4 ⁶	4	4 ⁶
IV	3	14-20	(³)	12	2	(³)	(³)	8-12
V	2	6	6	6	2	(³)	12	4 ⁶
VI	2	0.6	0.9	0.9	1	1.5	1.5	0.9
VII	3	1-2	3	-----	5	1-2	2	1-2
VIII	2	0.8	1	(³)	1	1	1	1
IX	0	-----	-----	-----	1	(³)	4-6	(³)
X	4	3	5	4-6	1	(³)	4-6	4-6
XI	0	-----	-----	-----	1	4	4	4

¹ If nothing else is mentioned this means cumulative doses administered within 4 to 7 hours.

² Alterations in the magnitude amounting to at least 50% as compared to the controls.

³ Significant alterations could not be observed at the doses tested.
⁴ Single dose.

⁴ Single dose.

Some of the compounds synthetized have been tested 25 to determine their toxicity. The results obtained are shown in Table II.

Table II

Compound No.	LD ₅₀ in mg./kg. body weight			
	Mouse		Rat	Rabbit
	IV	IP	IP	IV
I		5-7		
II		12-25		
III	10	50	75	7
IV		125	100	17
VI		8		
IX		25-50		

IV = intravenously.

IV = intravenously.
IP = intraperitoneally.
ID = 'Intra dermally'

LD_{50} =the dose that kills 50% of the test animals.

Investigations carried out show that these new compounds neither block nor potentiate the action of substances affecting the autonomic nervous system when administered in a dosage sufficient to suspend or prevent heart arrhythmias. Experiments carried out prove that the cardiovascular effects initiated by the quaternary compounds of the present invention are specific to heart and peripheral blood vessels.

For an evaluation of the importance of the length of the application time, compound No. IV was tested in "coronary dogs." It appears from this that the injection in the course of a five minute period of 8 to 10 mg./kg. body weight procured a considerable lowering of the blood pressure while this effect did not come forth if the application time was prolonged to 35 to 45 minutes.

The new compounds synthesized according to the present invention are valuable for the treatment of different kinds of heart arrhythmias arising from the auricular as well as the ventricular part of the heart and may be administered according to generally used methods in the form of different preparation forms, as for instance, granulates, capsules, tablets, suppositories, aerosols and solutions and suspensions intended for parenteral as well as peroral use.

We claim:

1. The compound

10. The compound

5

14. A compound having the formula

wherein A and B are selected from the group consisting of straight and branched alkynes having 1 to 4 carbon atoms; R₃ and R₄ are selected from the group consisting of lower alkyl, and lower alkoxy; n and m are integers from 0 to 3; Z[⊕] is selected from the group consisting of

11. The compound

10

12. The compound

15

20

wherein R₁ and R₂ are alkyl having from 1 to 3 carbon atoms, and R₆ is alkylene having from 1 to 4 carbon atoms; and X[⊖] is the anion of a physiologically acceptable acid.

13. The compound
